UNITED STATES PATENT OFFICE

2,607,477

DISPLAY AND PACKAGING DEVICE FOR HARDWARE ARTICLES

Fred Gerson, Elmhurst, N. Y.

Application March 11, 1948, Serial No. 14,284

6 Claims. (Cl. 206—80)

1

The present invention relates to combination display and packaging devices and refers more particularly to devices of this type for use in connection with hardware articles and the like.

It is an object of the invention to provide a display and packaging device of the aforesaid nature which is very compact and sturdy in construction, uses a minimum of material and may be conveniently stacked and without injury or damage to the article secured to said device.

It is another object of the invention to provide means facilitating installation of the article on the display and packaging device substantially in its normal or operative position so that the purchaser will be enabled to readily visualize the function of the article with its movable parts and the position of its anchoring or fastening elements.

A still further object of the invention is to provide means permitting the attachment of any accessory parts within the confines of the display and packaging device so that these parts do not interfere when a plurality of such display devices are stacked for shipping or other purposes.

It is another object of the invention to provide means offering the possibility of reinforcing the display and packaging device by the employment of certain parts of the article secured to such device.

Still a further object of this invention is to provide means enabling unskilled labor to speedily and readily install a hardware or similar article in accordance with the display position on the display and packaging device on which said article may be mounted.

Still another object of the invention is to provide means affording the assemblage of a hardware or similar article with the display and packaging device in a manner substantially corresponding to the position of the article which it assumes in practice, for instance on a carrier such as a door, whereby also the thickness of such carrier with which such hardware article may be associated becomes apparent from the form of the display and packaging device.

These and other objects of the invention will be pointed out in the following description and claims and illustrated in the accompanying drawing which discloses, by way of example, the principle of the invention and preferred modes which have been contemplated for applying said principle.

In the drawing:

Fig. 1 shows a side elevational view of a display and packaging device made in accordance with

2

the invention and carrying an article, the latter being partly shown in section.

Fig. 2 is a rear elevational view of Fig. 1.

Fig. 3 is a sectional view taken along line 3—3 of Fig. 1.

Fig. 4 is a side elevational view and

Fig. 5 is a rear elevational view of a display and packaging device made in accordance with this invention and shown in a modified form.

10 Fig. 6 is a sectional view taken along line 6—6 of Fig. 4.

Fig. 7 is a front elevational view of a display and packaging device in accordance with the invention and shown in a further modified form.

15 Fig. 8 is a sectional view through the center of the display and packaging device of Fig. 7 with the article thereof omitted.

Referring now more particularly to the drawing there is disclosed in Figs. 1 and 3 a hollow

20 display and packaging device 10 which is substantially U-shaped in cross-section (Fig. 3). Device 10 is preferably made of relatively strong cardboard or pressboard material having the creases or folds 11 and 12 whereby the front and 25 rear walls 13 and 14 are formed which are spaced from each other a predetermined distance, which is indicated by the width of the web 15. The height of the packaging device 10 may be chosen according to the length of the article 16 which, in this instance, forms a handle with a push button mechanism 17 of known construction. Push button mechanism 17 includes the button proper 18, the rod member 19 which extends through opposite perforations 19a, 19b provided in the front 30 and rear walls 13 and 14, and further a housing 35 20 carrying the latch 21.

According to the present construction threaded fastening means or bolts 22 and 23 are employed to engage handle 16 at 22a and 23a where-

40 by said handle is fixed in simulated position of use on the front surface 24 of wall 13. Threaded bolts 22 and 23 extend from the outer surface 25 of wall 14 through openings 22b and 23b of rear wall 14 and openings 22a, 23a of wall 13 and 45 threadedly engage the respective rear surface portions 16a and 16b of handle 16. As can be further seen from Figs. 1 and 2 threaded bolt 22 holds in place on rear wall 14 housing 20 which is provided with upper flange openings

50 20a for the insertion of threaded bolt 22.

Lower flange openings 20b are provided which in this particular instance are employed to removably hold in place the lower part of housing 20 by means of a staple 26 which passes through 55 opening 20b and wall 14 to hold on its rear face

3

21 a bag-shaped member 28 which is preferably coextensive with the width of rear wall 14 and is adapted to hold therein any supplementary parts of handle 16 if desired.

As can be further seen from Figs. 1 and 2 washers 29 may be employed to cover the perforation 23b provided in rear wall 14 to permit easy passage of threaded bolt 23.

From the foregoing it can be easily gathered that handle 16 with its cut-out 30 may be held by the fingers of the hand while the thumb of the hand is actuating the push button mechanism 17 for demonstration and similar purposes. It goes without saying that the construction of the device 10 lends itself to the placing of a plurality of display and packaging devices next to each other for stacking and shipping purposes without occupying an unduly large space.

Figs. 4 and 5 illustrate a further embodiment of this invention in which a simplified handle 41 is placed with its abutment surface 42 against the outer or front surface 43 of a display and packaging device 40. This device consists of a substantially straight cardboard piece or panel 44 having a central U-shaped web 45 with parallel and juxtaposed walls integral with said cardboard piece 44 but directed at right angles or perpendicular to the front face 43 thereof as can be seen from Fig. 4.

Web 45 may be held in place by securing means, such as staples 46, 47, 48 and may be employed to receive through suitable openings 49 and 50 thereof threaded bolts 51 and 52 carrying washers 51a and 52a which bolts are substantially enclosed by the juxtaposed walls of said web and are used when mounting handle 41 on a door or the like (not shown) to hold handle 41 in place with respect to such door. In this particular instance handle 41 is mounted on display device 40 in the same manner as if display device 40 were the door wall with the height of web 45 demonstrating the approximate thickness of the door wall as may be easily visualized from Figs. 4 and 5.

It is well understood that the handle 41 per se is of known construction having the cut-out 53 for the insertion of the fingers of a hand.

It will be further realized from Figs. 4 to 6 that the simplified display device 40 reinforced at its web 45 is held in firm position with respect to the remainder of the display device 40 by means of the bolts 51, 52. It is obvious that the front surface of the display and packaging device 40 may carry any instructions for the employment of the article as well as any advertising matter (not shown).

Figs. 7 and 8 show a display and packaging device 60 in a further simplified form. Device 60 consists principally of a sheet or piece of cardboard 61, provided with a horizontally extending U-shaped folded web 62, directed forwardly of the front face of cardboard panel 60 and having a depending portion 63 which is integrally formed with cardboard pieces 61.

Horizontally extending U-shaped fold or web 62 is provided with a row of vertical and registering openings 64, 65 through which fastening means in the form of screw bolts 66, 66a, 66b, 66c pass which by means of threaded portions thereof firmly hold web 62 in its angular position with respect to the remainder of cardboard piece 61. The upper portion of the display device 60 is provided with an opening 67 behind which extends a tongue member 68 struck out of the piece 61 for retaining thereat a hardware article 70.

4

in the form of a known structure consisting of strike 71 and catch 72. Catch 72 has the attaching plate 73 with an upper extension 74, the latter being adapted for insertion through opening 67 and is retained in this position by means of tongue 68, so that catch 72 partly extends to the rear face 69 of display device 60. Strike 71 is connected to two perforated flange portions 75, 76 and supported by the upper wall of web 62 to which said flange portions are applied. Screw bolt 66a and 66b extend and hold strike 71 in position on the upper surface of web 62. It will become apparent that strike 71 is thus displayed and held in its applied position with respect to catch jaws 72, 72b.

It will be further obvious from Figs. 7 and 8 that the threads of screws 66a and 66b when engaging said openings 64 and 65 of web 62 will hold the juxtaposed web walls in a firm position and abutting relation to each other as indicated in Fig. 8. This display and packaging device 60 demonstrates the distance and the position of the screw bolts 66a, 66b with respect to the openings 71 and 78 for securing, respectively, strike 71 and catch 72 in position on a wall adjacent a door opening with which the door will operate, as is well understood.

It can thus be seen that there has been provided in accordance with the present invention a display and packaging device for hardware and like article including parts with openings for the passage of fastening means for said article; comprising a plate carrier or panel provided with a portion U-shaped in cross-section, said U-shaped portion being provided with parallel walls in contact with each other and having a plurality of perforations, respectively, in registry with one another, said fastening means passing through said openings for the engagement with said article to thereby fix said article in simulated position of use on said carrier.

The aforesaid U-shaped portion may be directed substantially perpendicular to the remainder of said panel.

A modification of the device may be made according to which said portion may extend perpendicular to and rearwardly of the remainder of said carrier and said opposite faces of said carrier portion extend substantially parallel to each other and form a hollow space therebetween for the accommodation of an accessory therein.

Having thus described the invention, what is claimed as new and desired to be secured by Letters Patent, is:

1. A display and packaging device for hardware and like articles including fastening means therefore, comprising a panel having a front face to which said article is applied for simulating position of use, and folded web means integral with said panel and extending angularly to said front face, said web means including juxtaposed walls in contact with one another, one of said walls being spaced from said panel and provided with openings, said fastening means passing through said openings for engagement with said article, whereby a portion of said fastening means spaced from said article abuts against at least one of said walls of said web means.

2. A device according to claim 1, wherein said web means extends at right angle to and rearwardly of said front face of said panel.

3. A device according to claim 1, wherein said web means substantially encloses said fastening

means when the latter is in engagement with said article.

4. A device according to claim 1, wherein said walls are spaced from each other at locations of said fastening means when in engagement with said article, and means securing said walls to each other at the remaining portions of said web means.

5. A device according to claim 1, wherein said walls are maintained in contact with each other by staples.

6. A display and packaging device for hardware and like articles including fastening means therefor, comprising a panel having a front face to which said article is applied for simulating position of use, folded web means integral with said panel and extending angularly to said front face, said web means including juxtaposed walls in contact with one another, one of said

walls being spaced from said panel and provided with openings, said fastening means passing through said openings for engagement with said article, whereby a portion of said fastening means spaced from said article abuts against at least one of said walls of said web means, and securing means passing through said walls and maintaining the latter in substantially parallel and abutting relation to each other.
